(57) **CLAIM**

The ornamental design for a bottle accessory, as shown and described.

DESCRIPTION

FIG. 1 is a perspective view of a first embodiment of a bottle accessory showing my new design in a used condition; FIG. 2 is a perspective view of a second embodiment of a bottle accessory in a used condition;

FIG. 3 is a top view of FIG. 1 in a flat position;

FIG. 4 is a top view of FIG. 2 in a flat position;

FIG. 5 is a top view of a third embodiment of a bottle accessory in a flat position;

FIG. 6 is a top view of a fourth embodiment of a bottle accessory in a flat position;

FIG. 7 is a bottom view of FIG. 3 shown in a flat position, the bottom view of FIGS. 4–6 are identical;

FIG. 8 is a front view of FIG. 1 shown in a used condition;

FIG. 9 is a front view of FIG. 2 shown in a used condition;

FIG. 10 is a rear view of FIG. 8 shown in a used condition;

FIG. 11 is a left side view of FIG. 8 shown in a used condition;

FIG. 12 is a left side view of FIG. 9 shown in a used condition;

FIG. 13 is a right side view of FIG. 8 shown in a used condition;

FIG. 14 is a right side view of FIG. 9 shown in a used condition;

FIG. 15 is a top view of FIG. 8 shown in a used condition, the top view of FIGS. 4–6 in used condition are identical;

FIG. 16 is a bottom view of FIG. 8 shown in a used condition, the bottom view of FIGS. 4–6 in a used condition are identical; and,

FIG. 17 is a perspective view of FIG. 6.

The dotted lines shown in the drawings are not considered part of the claimed design, and all sides not shown form no part of the claimed design.
